PULSE MODULATION SYSTEM

William Arnold Beatty and Charles Thomas Sculley, London, England, assignors to International Standard Electric Corporation, New York, N. Y.

Application August 22, 1940, Serial No. 353,688
In Great Britain October 13, 1939

4 Claims. (Cl. 179—171.5)

This invention relates to methods of producing a radio frequency carrier signal which is modulated by time modulated pulses.

In high frequency transmitting systems utilising time modulated pulses, it is possible to first generate the time modulated pulses and to then utilise these pulses for the purpose of modulating the carrier wave. There are certain disadvantages in this procedure in that should a large pulse voltage be required for high power modulation, it becomes necessary to amplify the pulse by means of a high quality amplifying system which does not distort the initial shape of the pulse.

The present invention resides in a system for producing a carrier wave, amplitude-modulated by time-modulated pulses wherein an electron beam, which is deflected across a target in such a way as to set up time-modulated pulses, is modulated in intensity at carrier frequency.

One advantage thereby achieved is that the necessity of amplifying a time-modulated D. C. pulse signal is obviated.

The invention is a development of the method of generating pulses described in pending U. S. patent application Ser. No. 312,645, filed January 6, 1940, and U. S. Patent 2,256,336, issued September 16, 1941, the development being the radio frequency modulation of an electron beam which is being repeatedly deflected across one or more targets under the control of a wave of constant form and which is deflected transversely of the first deflection under the control of a sound or like wave for the purpose of producing a pulse modulated radio frequency carrier in which the various pulses are time modulated in such a manner as to have a time function characteristic of said sound or like wave.

The description which follows may be more readily understood by referring to the accompanying drawing, in which Fig. 1 illustrates a system according to the invention, while Figs. 2 and 3 illustrate target forms suitable for use therein.

Referring to Fig. 1 of the drawings there is shown a cathode ray tube of a type suitable for the generation of time modulated pulses as described in the aforementioned patent application and patent above identified. The tube elements are indicated as follows, cathode 11, control grid 12, focussing anode 13, final anode 14, deflector plates 15, aquadag ring anode 16, and two target electrodes 17 and 18. The various D. C. operating voltages and circuits are not shown as these follow well known cathode ray tube practice.

10 The deflector plates are shown as excited by sweep wave source 38 and speech wave source 31, respectively. In the aforementioned patent applications, the electron beam is assumed to have a constant value while it is being deflected across the target plates, except during the fly back period when preferably it is completely suppressed, this being achieved by the application of a negative voltage between the cathode 11 and the control grid 12.

15 It is now proposed that the beam be modulated at a radio frequency during such time as it is not suppressed in the fly back period. A source of radio frequency 19 is coupled by the tuned circuit 20, 21 to the control grid 12 and cathode 11, the control grid by means not shown being normally biased to cut off. The effect of the radio frequency drive is to give an electron beam modulated at radio frequency. The target plate 17 is coupled by means of tuned circuit 22, 23 to the final anode 14, which is at cathode potential for the carrier frequency. During such time as the beam strikes the target plate 17, a radio frequency at the same frequency as supplied by the input 19 is present in the circuit 22, 23. Since the period of time during which the beam can strike the target plate 17 is a function of the amplitude of the modulating signal it follows that the radio frequency signal is present in the circuit 22, 23 for periods of time which are functions of the amplitude of the modulating signal applied to one of the pairs of deflecting plates 15. The circuit 22, 23 is coupled to an output circuit 25, 26, the output being utilised in any desired manner.

25 Targets 17 and 18 may have any of the shapes disclosed in the application and patent previously mentioned (e. g. application Ser. No. 312,645 and Patent No. 2,256,336). Fig. 2 illustrates one suitable form for such targets, the two targets 17 and 18 being in this case connected together so as to form one V-shaped target.

30 In cases where it is desired to obtain a pulse signal of the type described in the aforementioned patent application Serial No. 312,645, i. e., a signal having one edge of an amplitude different to the remainder of the pulse, the second target 18 can be connected to the final anode 14 by another tuned circuit 27, 28, this circuit being also tuned to the frequency of the supply 19.

35 Fig. 3 illustrates suitable forms for targets 17 and 18 for such a case.

40 If the circuit 25, 26 is suitably coupled to the circuit 22, 23 and 27, 28 different amplitudes of

radio frequency signal can be injected into the circuit 25, 26 from the circuits 22, 23 and 27, 28, respectively.

In a practical embodiment the supply source 19 gives a radio frequency of 3 megacycles while the frequency of the time modulated pulses is 15 kilocycles per second. The 3 megacycle output in the circuit 25, 26 can be utilised to drive frequency multiplying circuits giving, for instance, a final output at a frequency of 48 megacycles.

During the fly back period the output can be suppressed either by back biasing the grid 12 or by suppressing the generation of the radio frequency at source 19. This can be done in any known manner.

What is claimed is:

1. Apparatus for producing a carrier wave amplitude-modulated by time-modulated pulses comprising a cathode-ray tube having a source of electrons, a target for receiving said electrons, whose effective shape determines the wave-form of said pulses, means for deflecting said electrons across said target, control means for regulating the number of electrons reaching said target, a source of carrier wave energy connected to said control means for modulating said electrons, and an output circuit connected to said target.

2. Apparatus for producing a carrier wave amplitude-modulated by time-modulated pulses comprising a cathode ray tube having means for

producing a beam of electrons, a target for receiving said electrons having at least two portions insulated from each other whose effective shapes determine the wave form of said pulses, first deflecting means for deflecting said beam in a first direction across said target, second deflecting means for deflecting said beam in a direction at an angle to said first direction, control means for regulating the number of electrons reaching said target, a source of carrier wave energy connected to said control means for modulating said beam, a source of sweep voltages connected to said first deflecting means, a source of modulating voltages connected to said second deflecting means, and an output circuit connected to said target.

3. Apparatus according to claim 2 wherein said target comprises a triangular effective portion, the legs of said triangular portion being parallel to said two directions, and a thin strip-like effective portion, parallel to the hypotenuse of said triangular portion.

4. Apparatus according to claim 3 wherein said output circuit comprises a first circuit connected to one of said target portions, a second circuit connected to the other of said target portions, and a third circuit coupled to said first and second circuits, the coupling between said first and third circuits being different from the coupling between said second and third circuits.
